UNITED STATES PATENT OFFICE.

JOHN G. LEWIS, OF ST. LOUIS, MISSOURI.

HEM OR SEAM FOR SEWED ARTICLES.

1,133,808.

Specification of Letters Patent. Patented Mar. 30, 1915.

Application filed August 7, 1911. Serial No. 642,619.

To all whom it may concern.

Be it known that I, JOHN G. LEWIS, a citizen of the United States, residing at city of St. Louis and State of Missouri, have invented certain new and useful Improvements in Hems or Seams for Sewed Articles, of which the following is a specification.

My invention consists in a seam for sewed articles wherein a main layer of textile or other goods and the edge of a superimposed layer are connected by a single row of en-chained stitches having their linear connections (between the loops) lying in a line on the main layer substantially parallel to the edge of the superimposed layer and adjacent to or beneath said edge, for effective concealment, each loop penetrating into the main layer and through the superimposed layer at an oblique angle, or inclination, to the edge of said superimposed layer, and the ends of the loops extending over the edge of the superimposed layer for holding the edge down by its enchainment with the next succeeding stitch. Such a stitch arrangement, which is susceptible of production by a blind stitch sewing machine, is very advantageous in felling, giving an edge retaining overseam loop for each needle penetration and a surface appearance simulating the effect of hand-felling.

In the drawings, wherein the parts are exaggeratedly shown for ease of tracing the thread formation, Figure 1 is a plan view of a seam embodying my invention; Fig. 2 is a section therethrough; Fig. 3 is a perspective thereof; and Figs. 4, 5 and 6 are views, respectively similar to Figs. 1, 2 and 3, showing a slightly different relation between the elements of the seam.

The same numerals are herein applied to like parts in all views.

10 indicates a base layer of textile or similar material on which is superimposed a layer 11, having an edge 12, to be secured to the main layer, the edge 12 being shown as formed by folding under a portion 13, of the superimposed layer, although the edge might, of course, be "raw" or unfolded.

10 The edge 12 is secured to the main layer 10 by a single series of chain stitches comprising a series of loops 14, penetrating into the main layer 10, and through the superimposed layer 11, to enter and emerge on the same side of the work, the portion 14^a of each loop buried in the goods lying at

an oblique angle to the edge of the superimposed layer; the loop end 14^b overlying the said edge and embracing the next succeeding loop at its point of entrance into the main layer, and the lineal connections 15 between the loops lying in a line substantially parallel with the edge of the superimposed layer and keying the loop extremities. The thread portion buried in the main layer need not penetrate clear through, and therefore the stitches may be "blind" on the one side of the work.

In forming the seam by machine work, the feed, as indicated by the arrows in Figs. 1, 3, 4 and 6, is preferably in a direction opposite to the lineal direction of needle thrust; and where the length of feed is substantially equal to the lineal extent of penetration the over-seaming loop ends 14^b lie at approximately right-angles to the edge of the superimposed layer, giving a particularly neat and attractive appearance to the seam. The point of entrance of the loop into the body material 10 may be close to the edge 12, as shown in Figs. 1 to 3, or under said edge as shown in Figs. 4 to 6 (the edge being lifted to facilitate the needle entrance, if necessary), so that the lineal connections 15, lying on the body layer parallel with the edge, are only slightly exposed or are wholly concealed, as may be preferred. As the angle of needle thrust to the edge of the superimposed layer may be made very small, a very narrow over-seaming loop extremity may be presented without shortening unduly the "bite" or burial of the stitch in the goods, so securing a firm anchorage of the relatively long buried portion 14^a of each loop in the material layers, and also giving such shortness to the overseaming loop-end 14^b as insures that the edge is held firmly and closely upon the main layer.

What I claim is:

1. A hem or seam for sewed articles comprising a main layer of material, a superimposed layer of material presenting an edge thereon, and a single row of single-thread chain stitches entering and emerging from the same side of the work comprising a series of loops penetrating into the main layer and through the superimposed layer in the general direction away from the preceding stitches at an oblique angle to said edge and thence passing across the edge at substantially right angles to the edge, said

loops being enchain'd at the surface of the main layer and the lineal connections keying said loops lying in a line on the main layer parallel with and close to the edge of the superimposed layer.

2. A hem or seam for sewed articles comprising a main layer of material, a superimposed layer presenting an edge thereon, and a single row of stitches entering and emerging on the same side of the work, comprising a series of loops penetrating into the main layer and through the superimposed layer in a general direction away from the

preceding stitches at an oblique angle to the said edge and thence passing over the edge 15 substantially at right angles thereto, said loops being enchain'd and the lineal connections keying said loops lying in a line on the main layer parallel with and beneath the edge of the superimposed layer. 20

In testimony whereof I hereunto affix my signature in the presence of two witnesses.

JOHN G. LEWIS.
